UNITED STATES PATENT OFFICE.

CHARLES MCKEEVER, OF JERSEY CITY, NEW JERSEY.

VEHICLE-LAMP.

1,253,848.

Specification of Letters Patent. Patented Jan. 15, 1918.

Application filed February 12, 1917. Serial No. 148,044.

To all whom it may concern:

Be it known that I, CHARLES MCKEEVER, a citizen of the United States, residing at Jersey City, county of Hudson, and State of New Jersey, have invented an Improvement in Vehicle-Lamps, of which the following is a specification.

My present invention relates to a vehicle lamp and particularly to lamps of this type in which electric lights are employed, and provided with a cup or cover of more or less translucent material to overcome the glare in ordinary vehicle lamps. The object of my invention is the provision of a vehicle lamp of this type in which the lamp bulb and electrical connections by which it is supported may be removed from the lamp and when desired employed for lighting purposes in making repairs where necessary in the event no other light is available.

In carrying out my invention I employ a lamp case preferably fitted with a reflector and having a shoulder in the axial center of the lamp adapted to act as a socket for the base of an electric light bulb and the electrical connections to the same. Together with these features, and as hereinbefore indicated, I also employ a cup or cover for the electric lamp bulb and means for supporting the same, the construction being such that the socket for the base of a light bulb is maintained in position in the lamp case by devices co-acting with the bulb of the lamp as will be hereinafter more particularly described.

In the drawings:

Figure 1 is a central transverse section illustrating my present invention.

Fig. 2 is a similar view showing a modified form of the invention, and

Fig. 3 is a plan of the cup and a support member therefor showing the manner in which these parts are connected.

Referring to the drawing and particularly to Figs. 1 and 3, in carrying out this invention I employ a lamp case or shell indicated at 10 and made of metal in the usual configuration. Axially this lamp case is provided with a shoulder 11 and is fitted with a reflector indicated at 12. The shoulder 11 is bored to receive a sleeve 13 which passes through the same and extends to the interior of the lamp at one end while the opposite end projects exteriorly of the shoulder. Both ends of this sleeve are

adapted to act as sockets, the inner end within the lamp to receive a light bulb base 14 of the electric light 15, and this end of the sleeve is slotted as indicated at 16 in the usual manner to receive the pins 17 on the light bulb case 14 so as to maintain the same in position. The sleeve 13 also contains a plug 18 in which contacts 19 are yieldingly mounted and adapted to bear against the terminals 20 of the electric light bulb base 14 when the latter is in position in the socket formed by the inner end of the sleeve. At the outer end the sleeve 13 is similarly slotted as indicated at 21 to receive the plug terminal of lead wires from any suitable source of electricity.

As shown in Fig. 1, the inner end of the sleeve 13 may terminate in a cup base 22; that is to say, the cup base 22 and the sleeve 13 may be made as an integral structure. The cup base 22 is flanged as indicated at 23 to receive the rim of a cup 24 made of translucent or other similar material to prevent the glaring effect of the light when surrounding the light bulb and secured in position. This cup 24 is secured in the cup base 22 by means of lugs 25 turned in from the rim of the cup base, and the ribs 26 provided on the outer surface of the cup 24 adjacent the edge thereof, it being understood that the open end of the cup is placed within the rim 23 and given a partial turn so as to cause the ribs 26 to engage the under edges of the lugs 25 in order to secure the cup in position.

When properly placed, as will be seen in Fig. 1, the cup base 22 bears against the adjacent portion of the reflector 12, and the sleeve 13, and the cup base are secured in this position by a collar 27, provided with a set screw 28, fitted on the sleeve exteriorly of the shoulder, with which when fixed in place, the collar 27 contacts.

By reference to Fig. 2, it will be seen that instead of forming the cup base with the socket sleeve, that these may be separate members, the sleeve 29 in this instance being plain ended, and the cup base 30 formed as an integral part of the reflector 12.

In either or similar constructions it will now be apparent that the electric light bulb and its mounting may be readily removed from the lamp case and used if necessary for lighting purposes in making repairs when light is not otherwise available, as herein-

before indicated. In doing this it will be necessary of course to uncouple the plug fitting in the socket in the outer end of the sleeve; to loosen the set screw 28, and re-
5 move the collar 27, when the sleeve with the lamp bulb will be readily removable, and then by again coupling the contact plug in the socket formed in the outer end of the sleeve, the light will be available for use
10 in any place which the length of the lead wires will permit.

I claim as my invention:

1. In a vehicle lamp a case, a sleeve removably mounted in said case and having
15 sockets at both ends thereof, a socket for a cup member associated with the inner end of the sleeve and adapted to prevent the outward movement thereof, and means associated with the sleeve exteriorly of the case
20 for normally preventing the inward movement of the sleeve.

2. In a vehicle lamp a case, a sleeve removably mounted in said case and having sockets at both ends thereof, a socket for a cup member associated with the inner end of the sleeve and adapted to prevent an outward movement thereof, and a collar mounted on the sleeve exterior of the case for normally preventing an inward movement of the
25 sleeve.

3. In a vehicle lamp, a case, a sleeve mounted axially in the said case and provided with sockets at the ends thereof, an electric light bulb, the base of which is receivable in the socket at the inner end of
30

the sleeve, a cup member surrounding the said light bulb, means associated with the sleeve for securing the cup member in position, and means for securing the sleeve in position relatively to the case.

40

4. In a vehicle lamp, a case, a sleeve passing through a bore provided axially in the case and fitted within the case with a cup base, an electric lamp bulb, the base of which is fitted into the sleeve at the inner end thereof within the case, a cup surrounding the light bulb and adapted to be received and held in place in the said cup base, and means for securing the said sleeve and cup base in position relatively to the said case.

45

5. In a vehicle lamp, a case having a shoulder thereon with a bore in the axial center of the case, a sleeve adapted to fit the said bore and provided at one end thereof with a cup base, a reflector within the case 55 and against which when in position the cup base contacts, a contact plug within the sleeve, an electric light bulb, the base of which is received in the socket provided therefor at the inner end of the sleeve, a 60 cup surrounding the light bulb and held in position in the said cup base, and a collar surrounding the said sleeve exteriorly of the case and adapted to bear against the end of the said shoulder to maintain the sleeve 65 and cup base with the lamp and cup in their relative positions.

Signed by me this 6th day of February, 1917.

CHARLES McKEEVER.
